(57) **CLAIM**

The ornamental design for a tool-free carrier for an optical drive, as shown and described.

DESCRIPTION

FIG. 1 is a top perspective view of a tool-free carrier for an optical drive;

FIG. 2 is a top perspective view of a tool-free carrier for an optical drive, showing also a mounting surface for the carrier and an optical drive to be inserted into the carrier; and,

FIG. 3 is a top perspective view of a tool-free carrier for an optical drive, which is mounted to the mounting surface and holding the optical drive.

The broken lines shown are included for the purpose of illustrating the unclaimed portions of the article and form no part of the claimed design.
